CLAIM

The ornamental design for a bottle portion, as shown and described.

DESCRIPTION

FIG. 1 is a perspective view of a bottle portion showing our new design;

FIG. 2 is a front view of the bottle portion depicted in FIG.

1, the opposite rear view and the side views being identical;

FIG. 3 is a bottom view of the bottle portion depicted in FIG. 2; and,

FIG. 4 is a top view of the bottle portion depicted in FIG. 2. The broken line environmental showing is for illustrative purposes only and does not form part of the claimed design.
